COMBINED CANE AND STAND

Philip Y. K.-Howat, Baltimore, Md.

Application December 14, 1936, Serial No. 115,862

10 Claims. (Cl. 135—47)

The invention has for an object to provide a novel combined cane and stand structure capable of being normally carried as a cane and, at will, adjusted to a condition for supporting the user in standing position at an elevation above the ground, the better to enable the user to observe parades, athletic events or the like.

In its more detailed nature the invention resides in the provision of a combined cane and stand structure comprising a cane body or shank portion and a handle portion, said shank portion being formed of articulated sections capable of being relatively positioned to provide a base or supporting section, a horizontal foot support section, and a vertical or stand support section.

Another object of the invention is to provide a structure of the character stated in which the base section includes a plurality of supporting legs and means for automatically spreading and positioning the legs upon adjustment of the structure to its stand supporting condition.

Another object of the invention is to provide, in a structure of the character stated, a handle portion vertically adjustable to suit the needs of use of various users.

With these and other objects in view which will more fully appear, the nature of the invention will be more clearly understood by following the description, the appended claims, and the several views illustrated in the accompanying drawing.

In the drawing:—

Figure 1 is a side elevation, illustrating the invention adjusted for being carried as a cane. Figure 2 is a view similar to Figure 1 illustrating the structure adjusted for use as a supporting stand.

Figure 3 is a horizontal section taken on the line 3—3 on Figure 1.

Figure 4 is a horizontal section taken on the line 4—4 on Figure 1.

Figure 5 is a horizontal section taken on the line 5—5 on Figure 1.

Figure 6 is a rear elevation.

My combined cane and stand support comprises a base section A, a foot support section B and a stand support section C. When in their normal end-to-end or aligned relation, shown in Figure 1, the sections together form a cane-like structure, but the sections may be adjusted to the condition shown in Figure 2 in which the structure can be used as a stand support for comfortably supporting a user in an upright position elevated above the ground.

The base section includes a body portion 5 connected by a knee joint 6 to the foot support section B. Hinged to the lower extremity of the body portion, as at 7, is a plurality of leg members 8 shaped at their lower ends as at 9 to meet, when collapsed, in a perfect solid end cir-

cle, and having their upper ends cut away at the inner faces, as at 10, to provide a central space 11.

A slide guide 12 is formed in the body portion 5, and a slide member 13 is slidably mounted in said guide and link-connected, as at 14, with the foot support section B. A plunger member 15 is movable with the slide member and extends into the space 11 between the upper ends of the legs where it is link-connected, as at 16, with the leg members 8 for a purpose that will soon become apparent.

The section B comprises a body portion 17 which is preferably rectangular in cross section and connected by a knee joint 18 with the section A. An elongated foot support platform member 19 is pivotally secured to the body member as at 20 so that it may be shifted to present its longitudinal axis in line with the aligned sections when positioned as shown in Figure 1, or transversely as shown in Figure 2 when the sections have been positioned in stand supporting relation.

Section C likewise includes a body member 21 preferably secured, as at 22, to the lower extremity of a tubular stand support member 23. A handle member 24 is telescopically, or vertically-adjustably mounted in the upper end of the member 23, as at 25, any suitable means 26 being provided for securing the handle member in various degrees of projection from the end of said member.

Normally the structure may be carried as a cane with the sections A, B and C aligned as shown in Figure 1. Should the user be desirous of obtaining a point of vantage at a parade, athletic event or the like, where it is found difficult to see because of massed crowds, it is only necessary to adjust or reposition the sections of the structure as shown in Figure 2 whereupon the user can place the base upon a good ground support and stand upon the elevated platform member 19, using the stand support section as a convenient hand hold and rest.

It will be obvious that as the sections A and B are moved relatively between the positions shown respectively in Figures 1 and 2, the link connection 14 will impart sliding movement in one direction or the other to the slide member 13, and this movement will be transmitted to the plunger 15 and links 16, causing the leg members to move to their extended positions or from their extended to their collapsed positions depending upon the direction of said relative movement.

It is to be understood that the component parts of my improved device may be constructed of various materials and in any suitable dimensions, also that the details of construction may be variously changed without departing from the

spirit of the invention as particularly pointed out in the appended claims.

I claim:

1. In a device of the character described, the combination of a handle portion, and a shank portion, said shank portion being composed of articulated sections adjustable to position for providing a supporting base section, a horizontal foot support section, and a vertical hand support section.
2. In a device of the character described, the combination of a handle portion, and a shank portion, said shank portion being composed of articulated sections adjustable to position for providing a supporting base section, a horizontal foot support section, and a vertical hand support section, and means for vertically-adjustably supporting said handle section on said hand support section.
3. In a device of the character described, the combination of a handle portion, and a shank portion, said shank portion being composed of articulated sections adjustable to position for providing a supporting base section, a horizontal foot support section, and a vertical hand support section, an elongated platform shiftably supported on said foot support section to enable positioning thereof transversely of said foot support section.
4. In a device of the character described, the combination of a handle portion, and a shank portion, said shank portion being composed of articulated sections adjustable to position for providing a supporting base section, a horizontal foot support section, and a vertical hand support section, said base section including a plurality of legs and mounting means therefor enabling spreading of the legs for supporting purposes.
5. In a device of the character described, the combination of a handle portion, and a shank portion, said shank portion being composed of articulated sections adjustable to position for providing a supporting base section, a horizontal foot support section, and a vertical hand support section, said base section including a plurality of legs and mounting means therefor enabling spreading of the legs for supporting purposes, and means operable incident to the adjustment of the foot support section to its foot supporting position for spreading said legs.
6. In a device of the character described, the combination of a handle portion, and a shank portion, said shank portion being composed of articulated sections adjustable to position for providing a supporting base section, a horizontal foot support section, and a vertical hand support section, an elongated platform shiftably supported on said foot support section to enable positioning thereof transversely of said foot support section, said base section including a plurality of legs and mounting means, therefor enabling spreading of the legs for supporting purposes, and means operable incident to the adjustment of the foot support section to its foot supporting position for spreading said legs.
7. An elongated cane-like body comprising a base section, a foot support section and a hand support section, said sections being knee-hinge-connected to enable adjustment thereof from a longitudinally aligned condition to a condition in which the base and hand support sections assume substantially vertical positions, and the foot support section a horizontal position, and an elongated platform member shiftably supported on the foot support section to enable presentation of its longitudinal axis in line with the common axis of the body when the body sections are positioned in alignment and transversely of the foot support section when it is horizontally disposed.
8. An elongated cane-like body comprising a base section, a foot support section and a hand support section, said sections being knee-hinge-connected to enable adjustment thereof from a longitudinally aligned condition to a condition in which the base and hand support sections assume substantially vertical positions, and the foot support section a horizontal position, and an elongated platform member shiftably supported on the foot support section to enable presentation of its longitudinal axis in line with the common axis of the body when the body sections are positioned in alignment and transversely of the foot support section when it is horizontally disposed, said base section including a plurality of legs and mounting means therefor enabling spreading of the legs for supporting purposes.
9. An elongated cane-like body comprising a base section, a foot support section and a hand support section, said sections being knee-hinge-connected to enable adjustment thereof from a longitudinally aligned condition to a condition in which the base and hand support sections assume substantially vertical positions and the foot support section a horizontal position, said base section including a plurality of legs hingedly mounted to permit spreading thereof for supporting purposes and having a slide guide therein, a slide member movable in the guide and link-connected to said legs and to the foot support section whereby when the foot support section is moved to or from horizontal position its movement will be transmitted through the links and slide members to effect a spreading or contracting of said legs.
10. An elongated cane-like body comprising a base section, a foot support section and a hand support section, said sections being knee-hinge-connected to enable adjustment thereof from a longitudinally aligned condition to a condition in which the base and hand supporting sections assume substantially vertical positions and the foot support section a horizontal position, said base section including a plurality of legs hingedly mounted to permit spreading thereof for supporting purposes and having a slide guide therein, a slide member movable in the guide and link-connected to said legs and to the foot support section whereby when the foot support section is moved to or from horizontal position its movement will be transmitted through the links and slide members to effect a spreading or contracting of said legs, an elongated platform member shiftably supported on the foot support section to enable presentation of its longitudinal axis in line with the common axis of the body when the body sections are positioned in alignment and transversely of the foot support section when it is horizontally disposed, and a handle member vertically-adjustably mounted on said stand support section.

PHILIP Y. K.-HOWAT.
